[57] **CLAIM**

The ornamental design for an adjustable hand strap for use with binoculars, as shown and described.

DESCRIPTION

FIG. 1 is a top plan view of an adjustable hand strap for use with binoculars, showing our new design;
FIG. 2 is a right side elevational view, the left side being substantially the same;

FIG. 3 is a bottom plan view thereof;

FIG. 4 is a top perspective view thereof;

FIG. 5 is a bottom perspective view thereof;

FIG. 6 is a top perspective view similar to FIG. 4 but showing the adjustable strap separated from a padded portion;

FIG. 7 is a perspective view showing claimed design in position on binoculars; and,

FIG. 8 is another perspective view thereof.

The broken line showing of binoculars in FIGS. 7 and 8 is for illustrative purposes only and forms no part of the claimed design.
